(57) **CLAIM**

The ornamental design for a frame for a panel, as shown and described.

DESCRIPTION

FIG. 1 is a front bottom perspective view of a frame for a panel showing my new design;

FIG. 2 is a front top perspective view thereof;

FIG. 3 is an enlarged view of the design shown in FIG. 2;

FIG. 4 is a left side view thereof;

FIG. 5 is a right side view thereof;

FIG. 6 is a front view thereof;

FIG. 7 is a rear view thereof;

FIG. 8 is a top view thereof; and,

FIG. 9 is a bottom view thereof.

The broken lines immediately adjacent to the ends of the frame for a panel, represent the bounds of the claimed design and form no part thereof. The broken lines in FIGS. 1, 2, 4-9 are to show environment and form no part of the claimed design. The broken lines within the claimed areas are for the purpose of illustrating portions of the frame for a panel, which form no part of the claimed design.
